UNITED STATES PATENT OFFICE.

DAVID GOULD, OF PLAINVILLE, CONNECTICUT.

BOX.

1,043,690.

Specification of Letters Patent.

Patented Nov. 5, 1912.

Application filed September 26, 1911. Serial No. 651,346.

To all whom it may concern:

Be it known that I, DAVID GOULD, a citizen of the United States, residing at Plainville, in the county of Hartford and State of Connecticut, have invented new and useful Improvements in Boxes, of which the following is a specification.

An object of the invention is to provide a container, the closure of which is adapted to lock with the container when the same is properly positioned thereon.

My invention is particularly adaptable for use in connection with confectionery boxes and the like to lock the cover of the box with the box when the same is properly positioned thereon so that when the cover is removed from the box the same will be partially destroyed, thus preventing other persons from employing the box to accommodate other articles than those that were originally intended for the box.

Reference is to be had to the accompanying drawings constituting a part of this specification, in which similar characters of reference denote corresponding parts in all the views, and in which—

Figure 1 is a perspective view of my device. Fig. 2 is a side elevation, parts being broken away to disclose the underlying structure. Fig. 3 is a perspective view of the hook of my device. Fig. 4 is a perspective view of the locking lug of my device.

Referring to the views, I provide a container 10 having a cover 11 for removable engagement with the container as shown in Fig. 1. At one end of the cover 11 a weakened portion 12 is formed in any suitable manner and secured to the weakened portion 12 is a hook 13 provided with integral gripping lugs 14 for securing the hook to the weakened portion 12, the said hook being adapted to depend in the container 10 and having the lower end curved at 15, the said hook being provided with a lateral extension 16 adapted to abut against the under side of the cover 11 as will be seen by referring to Fig. 2. A locking lug 17 having the ends thereof bent and formed into integral gripping lugs 18, is adapted to be connected to one end of the container 10, a main plate 19 of the locking lug being spaced a dis-

tance from that end of the container to which the locking lug is secured.

In the use of my device the container 10 is first filled with the article adapted to be packed in the container and the cover 11 is then engaged with the container in the usual manner. As the cover 11 is moved into engagement with the container 10 the hook 13 will pass between the plate 19 and the end of the container to which the locking lug 17 is secured, the hook 13 is preferably made of a flexible material and when the bent portion 15 of the hook is passed beyond the plate 19, that portion of the hook will tend to spring outwardly so that if an attempt is made to remove the cover from the container, the hook will engage the locking lug 17, thus preventing the cover from being removed from the container as will be readily understood by referring to Fig. 2. When it is desired to uncover the contents of the container 10 the cover is removed in the usual manner and in doing so, the weakened portion 12 will break away from the cover 11, thus making it possible to entirely remove the cover from engagement with the container 10. By breaking the weakened portion 12, the cover will be mutilated to such an extent that it will be very impractical to attempt to either repair the cover or reuse the container 10 or cover 11 for the reception of other articles.

Although for the purpose of describing my invention I have shown a particular construction thereof and have disclosed a particular container, it will be understood that I do not limit myself to the mentioned construction and that containers of various sizes and dimensions can be employed, the scope of the invention being defined in the appended claim.

Having thus fully described the invention, what I claim as new, is—

As a new article of manufacture, the combination with a container provided with a removable cover having a weakened portion formed therewith, of a hook member depending from the under side of the said weakened portion, the said hook member consisting of a single piece of material bent to form a lateral extension abutting against

the under side of the weakened portion and terminating in gripping lugs extending transversely through the said weakened portion, and a locking lug on the said container and partially spaced therefrom to be engaged by an upwardly curved portion of the said hook member.

In testimony whereof I affix my signature in presence of two witnesses.

DAVID GOULD.
